UNITED STATES PATENT OFFICE.

CLARENCE H. GUPTAIL, OF ELGIN, ILLINOIS.

PUMP.

1,242,685.

Specification of Letters Patent.

Patented Oct. 9, 1917.

Application filed February 19, 1917. Serial No. 149,576.

To all whom it may concern:

Be it known that I, CLARENCE H. GUPTAIL, a citizen of the United States, residing at Elgin, in the county of Kane and 5 State of Illinois, have invented certain new and useful Improvements in Pumps, of which the following is a specification.

This invention relates to a pumping apparatus, and particularly to an air pump designed especially, although not necessarily, for the inflation of the tires of automobile wheels, and comprises a compact, strong, and powerful double acting pump which may be mounted upon the running board at 10 one side of the motor vehicle and protected from injury, dirt, and rain by a suitable casing inclosing the same, the pump being at all times contained therein and having a cover hinged to the casing and preferably 15 provided with a lock.

Another object of the invention is to provide an air pump comprising two double acting cylinders and means for operating the pistons in the two cylinders simultaneously, and so provided with directing means 20 as to separate from the delivery pipe one of said cylinders when a limited amount of air only is needed for use.

A further object of the invention is to 25 provide a simple, and strong pump for the purpose of inflating tires comprising two double acting cylinders, each of which cylinders is formed of a tubular member containing a piston, a head threaded on each 30 end, and a diaphragm screwed into the cylinder adjacent each end for the seating of induction and eduction valves which are automatically opened and closed by pressure of air as the piston reciprocates. In addition 35 this pump is so constructed that there will be no waste or lost motion between the operating handle and the piston stroke, and through the arrangement of levers there is a mechanical advantage not found in the 40 pumps now in use.

With the above as the principal objects in view, the invention consists of the novel construction, combination and arrangement of parts hereinafter described, pointed out 45 in the appended claims, and illustrated in the accompanying drawings, in which—

Figure 1 is an elevation of the complete pumping mechanism within its casing and secured to the running-board of a motor- 50 vehicle, said casing being partly broken

away, and one of the cylinders being shown in vertical longitudinal section,

Fig. 2 is a top plan view of the complete pumping mechanism, the casing being shown in section on the line 2—2 of Fig. 1, 60

Fig. 3 is a vertical cross sectional view through the mechanism on the line 3—3 of Fig. 1,

Fig. 4 is an enlarged detail view through a valve provided for cutting off the delivery 65 of air from one of the cylinders, and

Fig. 5 is a sectional view of the valve on the line 5—5 of Fig. 4.

Referring to the drawings, 10 indicates a support of any kind, in the present instance, 70 being a portion of the running board of an automobile. Bolted to the running board at a suitable point in its length is a rectangular base plate 11 which may be mounted directly on the base 11, or, as in the present instance, placed within a casing 12, the base 11 fitting the casing snugly as shown and resting upon the bottom, through which bolts pass into the running-board 10. The casing is fitted with a cover 13, here shown 80 as hinged at 14, and which may be secured against unlawful opening by a lock fastened by a key 15.

Near each end of the base 11 is affixed a pump cylinder 16, said cylinders being arranged in line or in tandem, and spaced apart, each cylinder containing a piston 17, the two pistons being connected by a single piston rod 18, the ends of which are bolted to the two pistons 17. Each cylinder 90 16 is made of a straight cylindrical member 19 having an exterior and an interior screw thread at each end, one of which ends is screwed into a threaded opening in the side of a cylinder head 20 fitting the same air-tight and having projecting downwardly from its lower side, legs or feet 21 that rest upon the base 11 and are rigidly fastened thereto by bolts 22 passing through the feet and into the base 11. The 100 opposite end of the cylinder 16 is screwed into a threaded opening in a second cylinder head 23 also provided with feet 21 secured by bolts 22, this cylinder head 23 having a central opening therethrough for the passage of the piston rod 18, and is provided with a stuffing gland 24 to form an air-tight joint between the cylinder head and the piston rod.

Screwed into each end of the cylinder 16 110

is a supplemental head or diaphragm 25, each diaphragm being spaced a short distance from the cylinder heads to provide a chamber 26 between the said heads and the diaphragm, the space between the diaphragms 25 forming a run-way for the piston 17. Through each cylinder head 20 and 23 is bored or otherwise formed a port 27 for the inlet of air into the cylinder 16. A similar but larger port 28 is made in the diaphragm 25 in line with the port 27, the latter port 28 forming a seat for an inlet valve 29 provided with a stem 30 that projects into the chamber 26 and is surrounded by a coil spring 31 that tends to maintain the valve always within its seat, but which will open under suction within the cylinder to permit air to enter through the port 27. Surrounding the stem 30 and spring 31 and extending between the cylinder head 20 or 23 and the adjacent diaphragm 25 is a short section of pipe 32 connecting the ports 27 and 28 for the free passage of air therethrough when the valve 29 is open.

Screwed into threaded openings in the cylinder heads 20 and 23 are nipples 33 and 34, their outer ends carrying elbows 35 and 36 to the former of which is connected a section of pipe 37 extending laterally beyond the cylinder 16 while a second pipe 38 extends from the elbow 36 at an angle to the cylinder 16. In each of the diaphragms 25 there is made a port 39 preferably in line with the nipples 33 and 34 and controlled by an inwardly closing valve 40 around the stem 41 of which is coiled a spring 42 that normally tends to maintain the valve in its seat in the port 39. A short tube 43 surrounds the valve stem 41 and spring 42 and bridges the space in the chamber 26 between the cylinder head and the adjacent diaphragm, similar to the tube 32 of the inlet valve 29.

Both cylinders 16 are provided at each end with inlet valves and outlet valves such as described, and as each piston 17 in its respective cylinder is connected to an end of the common piston rod 18, movement of said rod will cause alternate suction in one end of the cylinder and a compression in the other end, the air under pressure passing out through valves 40 and into pipes 37 and 38, these latter pipes having suitable connection with a straight horizontal pipe or tube 44 that extends from end to end of the casing and is connected midway between the two cylinders 16 and near one side of the casing to a vertical pipe 45 on the upper end of which near the top of the casing 12 there is threaded a T-coupling 46, from one branch of which a flexible tube 47 extends, and it is provided on its free end with a coupling for connecting to the valve stem of an automobile tire. This tube when not in use will remain coiled within the casing 12.

The other branch of the T-coupling 46 preferably serves as a means for the connection of a pressure gage 48. The pipe 45 is open from end to end and has two lateral openings near its lower end threaded for the connecting ends of the tube 44 while the bottom is closed by a threaded plug 49 on the upper end of a round bracket 50 secured to the base 11.

Midway between the two cylinders 16 is fixed a standard 51 that projects upwardly from an extended base plate 52 bolted to the pump base 11 and having at its upper end near the plane of the top of the casing a bearing 53 through which is formed a horizontal opening to receive a rocking pin or shaft 54, the ends of which pin or shaft project laterally beyond the bearing 53 into hub members 55 of an operating lever 56 and affixed to said hub by transverse pins 57. The rocking lever as shown is designed to impart movement to the piston rod 18 and includes the two hubs 55 connected above the bearing 53 by a yoke or arch-like portion 58 from the center of which projects upwardly a rectangular boss 59 for the engagement and disengagement of the operating handle 60, shown in dotted lines in Fig. 2. Depending from the hubs 55 are two arms 61 parallel to each other and of equal length and each extending downwardly normally to the horizontal line of the piston rod 18. The lower end of these arms 61 are flattened and pivotally connected each to one end of a link 62, the opposite ends of said links are journaled on the ends of pins 63 that project laterally in opposite directions from a collar 64 fastened by a pinion 65 to the piston rod 18 at a suitable point in the length thereof.

The operating mechanism or handle described is connected to the piston rod in the most advantageous manner and at such angles as to utilize all the power put into the handle 60 for moving the pistons within the cylinders. None of this power is lost by change of leverage and through this arrangement, the angle of movement of the operating lever is reduced to the smallest extent, it moving only through an arc of about 40°.

Preferably each cylinder is surrounded by a jacket 66, the ends of which are seated in annular grooves in the piston heads 20 and 23 and spaced a short distance from the exterior surface of the piston. This space, if desired, may be filled with oil, while a lubricating device 67 on the top of each cylinder feeds oil thereinto to lubricate the piston.

The outlet pipe 38 of both cylinders may, if desired, be connected with the delivery tube 44 by an angular T-coupling 68 but preferably a coupling such as 69 is used in place of one of the couplings 68, the cou-

pling 69 having an extension 70 toward its outlet end and bored for a three-way valve 71, which may, when desired, on being turned in the proper direction, as in Fig. 4, 5 cause all the air pumped by the cylinders to pass out through the flexible tube 47 and be used. If a less amount of air be needed, a quarter turn of the valve 71 will connect the outlet pipes of one of the cylinders 16 10 with a waste opening 72 formed in the valve casing 70 and into which the three-way valve can be made to open.

What I claim is:

1. The combination in a pump of two cylinders arranged in axial line, a working piston in each cylinder, and a piston rod connected at its ends to said pistons, a transverse diaphragm crossing each end of each cylinder, inlet and outlet valves mounted 15 in said diaphragms, an outlet pipe from each end of the cylinder connected to a common discharge pipe, and manually operated lever mechanism connected to the piston rod for operating the pump.
2. The combination in a pump of two cylinders arranged in axial line and connected to a common base plate, a working piston in each cylinder, and a piston rod connected at its ends to said pistons for reciprocating 20 the same in said cylinders, a transverse diaphragm crossing each end of each cylinder a short distance within the ends thereof, a piston head screwed on the end of each cylinder and provided with inlet and outlet 25 ports, an inlet and an outlet valve mounted

in each of said diaphragms, an outlet pipe leading from the opposite ends of each cylinder and connected to a common delivery pipe, a standard between the cylinders, a rocking lever pivotally mounted on said 40 standard, and a link between one arm of said rocking lever and said piston rod for operating the pistons.

3. The combination in a pump of two cylinders arranged in axial line, each cylinder 45 comprising a straight tubular member having external and internal screw threads on each end, a diaphragm screwed into each end of a cylinder and extending across the same near the respective ends, a cylinder 50 head screwed on the outer end of each cylinder and closing the ends of the same, a piston in each cylinder movable longitudinally between said diaphragms, a piston rod connected at its ends to said pistons, inlet and 55 outlet valves mounted on each of said diaphragms, an outlet pipe upon each end of each cylinder joined by a coupling, and the latter connected to a common delivery pipe, one of said couplings containing a valve to 60 disconnect the cylinder of the same side from said delivery pipe, and rocking means connected to the piston rod for operating the pistons.

In testimony whereof I affix my signature 65 in presence of two witnesses.
